Richard Grove

BY *Chas B. Mann*

ATTORNEY.

UNITED STATES PATENT OFFICE.

RICHARD GROVE, OF NORTH LIMA, OHIO.

WASH-BOARD.

SPECIFICATION forming part of Letters Patent No. 360,384, dated March 29, 1887.

Application filed June 22, 1886. Serial No. 205,867. (No model.)

To all whom it may concern:

Be it known that I, RICHARD GROVE, a citizen of the United States, residing at North Lima, in the county of Mahoning and State of Ohio, have invented certain new and useful Improvements in Wire Wash-Boards, of which the following is a specification.

This invention relates to an improved wash-board, and is illustrated in the accompanying drawings, in which—

Figure 1 is a view of the improved wash-board. Fig. 2 is a longitudinal section of the wash-board on line down the center, omitting the wires. Fig. 3 is a cross-section of the wash-board taken on the line *y* through the center, omitting the wires. Fig. 4 is a view of the back board detached. Figs. 5, 6, and 7 show the different forms of twisted and braided wire that may be used in the manufacture of this wash-board.

The rubbing surface of this wash-board consists of twisted, braided, woven, or crimped wire.

The letter *A* designates the side bars, and *B* the board or back. The side bars, *A*, are connected by the top strip, *c*, and two cross-bars, *d*, the ends of which latter are mortised into the side bars. The back board, *B*, is secured to place by its side edges, *e*, entered in grooves *e'*, cut in the side bars and the top and bottom edge, each having a groove, *f*, which takes on the cross-bar *d*. If desired, nails may be driven through the side bars, *A*, and cross-bars *d* into the edges of the back board.

The twisted, braided, woven, or crimped wire *g* is secured to the back board in the form of oval or circular coils. Any convenient or suitable means may be employed for securing the wire to the back-board. Staples *h* may be used for this purpose. For staying the several coils, so as to keep the spaces *i* between them of uniform width, a wire crimped or bent to form upward-projecting shoulders may be used, like that designated *d* in my United States Patent No. 216,181, of June 3, 1879; or, instead of such stay-wire, a metal

strip suitably notched on one edge may be used like that designated *h* in my said patent. If desired, the wires *g* of the rubbing-surface may be soldered to said stay wire or strip. The wires comprising the rubbing-surface when coiled in this way on a level-surfaced board afford the advantage of presenting to the clothes, when grasped by the hand and rubbed up and down, a constantly-changing surface.

The wires comprising the rubbing-surface may be coiled on a back board, having a convex surface, *k*, as shown in the drawings. This back board on one surface is raised at the center, or slightly slopes from the center in all directions toward the edges. It is thus thickest at the center, and produces what is here termed the "convex surface." A wash-board made of wires and having this feature is found to be more effective.

The wires *g* of the rubbing-surface may be constructed in a variety of ways, of which examples are shown in Figs. 5, 6, and 7. In Fig. 5 two wires, *g*, are twisted together. In Fig. 6 one flat wire, *g*, is twisted or spiraled; and in Fig. 7 three wires, *g*, are twisted together.

The wires may be made of copper, iron, or steel, and galvanized or tinned to prevent oxidation.

Having described my invention, I claim and desire to secure by Letters Patent of the United States—

1. A wash-board having a back, *B*, and a rubbing-surface consisting of wires secured to the said back in the form of oval or circular coils, as set forth.

2. A wash-board having a back with a convex face, *k*, and wires coiled upon and secured to said convex face, as set forth.

In testimony whereof I affix my signature in the presence of two witnesses.

RICHARD GROVE.
